United States Patent Office

Des. 179,278
Patented Nov. 27, 1956

179,278

COMBINED CAKE TRAY AND COVER THEREFOR OR SIMILAR ARTICLE

Charles O. Bliss, Los Angeles, Calif.

Application July 17, 1956, Serial No. 42,269

Term of patent 14 years

(Cl. D44—1)

FIG. 1

FIG. 2

FIG. 3

Fig. 1 is a top plan view of a combined cake tray and cover therefor showing my new design;

Fig. 2 is a side view thereof; and

Fig. 3 is a top plan view of the tray with the cover removed.

I claim:

The ornamental design for a combined cake tray and cover therefor or similar article, substantially as shown.
